UNITED STATES PATENT OFFICE

PAUL A. MEEHAN, OF DAYTON, OHIO, ASSIGNOR TO SWINDELL-DRESSLER CORPORATION, OF PITTSBURGH, PENNSYLVANIA, A CORPORATION OF PENNSYLVANIA

KILN CAR

Original application filed August 23, 1928, Serial No. 301,503. Divided and this application filed August 14, 1930. Serial No. 475,161.

My present invention relates in general to the construction of cars or trucks used for supporting and moving metallic articles during an annealing or other heat treating process in a continuous kiln or furnace.

In annealing and analogous heat treating processes wherein metallic articles are progressively moved through a continuous tunnel kiln, it is an established practice to enclose the articles in a container supported on one or more of the cars. When the cars with the container in position are passed into the kiln and subjected to the gradually increasing temperatures therein, any gases within the container expand and tend to escape therefrom. When metallic articles containing carbon have been heated to approximately a red heat, the carbon reacts with any iron oxide present in the container to form an atmosphere within the box of almost pure carbon monoxide. No oxidation of the articles can occur as long as this reducing atmosphere is maintained in the container. After passing through the high temperature section of the kiln, the gases and articles in the container are gradually cooled and contract. The resultant lowering of the gas pressure therein permits the kiln chamber atmosphere or, if the car is then outside of the kiln, air, to be quickly drawn into the container. When this change in the container atmosphere occurs, the articles are rapidly oxidized.

This is especially harmful in the annealing of steel sheets subsequently used in forming automobile bodies as a surface finish of the highest degree is required for such use and cannot be attained if surface oxidization is allowed to take place during the annealing operation. In annealing such sheets, the sheets are arranged horizontally in one or more piles in each container. The upper sheets being less closely pressed together than the lower sheets of the pile will be subjected to substantial oxidization, while the lower sheets will develop blue or grey edges, which are also undesirable.

Oxidation of the sheets during or immediately after the annealing process can be prevented by maintaining the articles in a

reducing atmosphere until they are cooled to substantially their final temperature and preferably, by continuously introducing reducing gases into the container during the annealing process and particularly during the cooling period thereof. In carrying out annealing operations of this character in a continuous tunnel kiln, it has been found extremely difficult to maintain the necessary supply of reducing gases to the containers on the moving cars while preventing the entrance of other gases therewith and waste of the gases supplied.

The object of my present invention is the provision of a kiln car construction capable of transporting heavy loads under the extreme thermal conditions required in the annealing of steel sheets and incorporating improved provisions for receiving a suitable gas from a source of supply and distributing it to all parts of a container mounted thereon and enclosing the sheets being heat treated.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described a preferred embodiment of the invention.

Of the drawings:

Fig. 1 is a sectional elevation of a tunnel kiln car embodying my invention;

Fig. 2 is a section on the line 2—2 of Fig. 1; and

Fig. 3 is an enlarged sectional view of a portion of the car shown in Figs. 1 and 2.

In the drawings I have illustrated a preferred embodiment of my invention in which a tunnel kiln A having the usual refractory side walls A' and crown A² is provided with a chamber or goods passageway B extending longitudinally of the kiln. The lower portion of the kiln chamber is provided with track rails B' at its bottom for kiln cars or trucks C. The kiln shown is of the muffle type, being heated by combustion chambers

B² resting on benches B³ at the side of the goods passageway. The combustion chambers B² through which products of combustion pass lengthwise of the kiln have their heating walls formed with the customary circulating channels B⁴, through which a convection current circulation of the kiln atmosphere is set up. In operation cars are inserted one at a time at the entrance end of the kiln and the train of cars normally filling the kiln is periodically advanced a car length by a car pusher (not shown) which may be of any suitable or usual type employed for the purpose. A new car is inserted at the entrance end of the kiln after each pushing operation.

Each of the goods carrying cars is preferably formed in three units, each of which comprises a body consisting of several massive blocks C' of refractory material supported on a metallic framework C², on the lower side of which a plurality of pairs of track engaging wheels C³ are suitably mounted. Each of the car units has a cast metal cover plate D extending over and protecting the upper sides of the refractory blocks C'. The cover plate is preferably divided into two sections D' and D² arranged in overlapping relation and each formed with a rib D³ projecting from its upper side and extending longitudinally of the car adjacent the outside edge of the section. A trough shaped groove or channel D⁴ with inclined sides and closed ends is formed in the upper side of each rib D³. A plurality of roller elements, such as cast iron or steel balls E, are mounted in each of the channels and form a support for a metal work support or tray G, which extends over the top of the assembled car units. The tray is formed at its underside with a pair of downwardly projecting longitudinally extending ribs G', each of which has a channel G² in which the tops of the balls E in the car units below are received. A marginal flange G³ is formed on the tray. Kiln cars constructed as heretofore described are disclosed in my prior Patent No. 1,641,185, granted September 6, 1927.

The metal sheets to be annealed are arranged horizontally in piles on the tray and covered by a removable metallic cover H, which, as shown, is formed of heavy metal plates and stiffening members riveted together. The cover is in the form of a box with a closed top and open bottom. Hooks H' are provided on the sides of the box H to permit engagement by a suitable hoisting mechanism (not shown) for lowering the box on to and lifting it off the tray. The top of each box H is provided at points adjacent its ends with one or more openings H² adapted to be closed by removable plugs H³. A sand seal H⁴ surrounds each plug and prevents the escape of gases from the interior of the box when the plugs are in posi-

tion. The plugs can be removed to permit any air within the box to be swept out before the box is passed into the kiln and also to permit the escape of reducing gases after the car is moved out of the kiln chamber. A fire clay seal H⁵ is also provided for sealing the line of contact between the lower edges of the box and the tray.

In carrying out my invention, one of the tray supporting balls in the central car unit is especially formed as hereinafter described to provide a conduit connection between the interior of the box and the portion of the kiln chamber below the car body. This ball element is designated as K and has its lower portion K' shaped to contact with the inclined sides of the groove D⁴ and shoulders K² resting on the upper surfaces of the cover plate rib as shown particularly in Fig. 3, and welded to the rib in that position. The ball K is formed with a vertical passage K³ therethrough and registering at its lower end with a vertical passage D⁵, extending through the subjacent rib D³ and refractory block C'. A pipe D⁶ extends upwardly through the passages D⁵ and K³ to the center portion of the ball K. A fluid nozzle K⁴ is mounted in the upper end of the passage K³ and formed with an axial passage K⁵, connected to the pipe D⁶. The nozzle projects upwardly into an enlarged vertical passage G³ formed in the tray G and rib G'. A shallow groove G⁴, into which the passage G³ opens, extends longitudinally in the tray bottom beneath the pile of sheets and provides a distribution of any gases from the pipe D⁶ to a series of transverse grooves G⁵ in the tray bottom. With this construction, any gas passing upwardly through the pipe D⁶ will be distributed throughout the space enclosed by the box H and tray G. A gas-tight connection between the ball K and rib G' is maintained by a shallow pan K⁶ surrounding and supported on the upper portion of the ball and lower end of the tray rib. The space between the pan K⁶ and rib G' is packed with fireclay, as shown in Fig. 3.

Various means may be provided for supplying a reducing gas such as natural gas, coke oven gas or producer gas to the boxes on the cars. In the construction illustrated, a supply pipe J is supported centrally beneath the metallic car frame C² and extends longitudinally thereof. This pipe is connected to the vertical pipe D⁶ by a lateral branch pipe J' in which a control valve J² is mounted. The pipe J is provided adjacent its ends with cut-off valves J³ and J⁴. A control valve J⁵ carrying a hose connection J⁶ is incorporated in the pipe J. The pipe J is also provided with a hose connection J⁷ at one end by which it is connected to the supply pipe J of the following car.

As disclosed in my prior application Serial No. 301,503, filed August 23, 1928, and

since matured into Patent No. 1,808,000, granted June 2, 1931, of which the present application is a division, the supply pipe J of each car may be connected to a source of reducing gas located in a pit adjacent the entrance end of the kiln in the manner described therein or to a suitable source movable with or carried by the cars. In either case, the supply of gas to the pipe D^o can be suitably regulated by the control valve J² to maintain a reducing atmosphere within the box during the portions of the annealing process requiring such conditions.

The car construction described is characterized by its mechanical strength, durability and avoidance of distortion of the exposed parts from thermal expansion and contraction. The location of the special supporting element K in the central car unit is not only beneficial from the point of gas distribution but also avoids any decrease in the thermal expansion and contraction properties of the construction. The construction and arrangement of the gas supply parts in the car is highly advantageous, permitting the maintenance of the supply of gas without waste thereof and avoiding any necessity of disassembling parts thereof to permit the removal of the tray G when desired.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention what I claim as new and desire to secure by Letters Patent, is:

1. A tunnel kiln car comprising a body, a plurality of supporting elements positioned on said body, a work supporting and enclosing container mounted on said supporting elements, and means for conveying a fluid through said body and one of said supporting elements to the interior of said container.

2. A tunnel kiln car having a metallic frame, a refractory body supported on said frame, a metallic cover mounted on said refractory body and having a groove in its upper side, a plurality of roller elements arranged in said groove, a work supporting and enclosing container mounted on said roller elements, and means for passing a fluid through said body and cover to the interior of said container.

3. A tunnel kiln car having a metallic frame, a refractory body supported on said frame, a metallic cover mounted on said refractory body having a groove in its upper

side, a plurality of supporting elements arranged in said groove, a work supporting and enclosing container mounted for thermal expansion and contraction on said supporting elements, and means for conveying a fluid through said body, cover and one of said supporting elements to the interior of said container. 70

4. A tunnel kiln car comprising a plurality of car units, each having a metallic frame, a refractory body supported on said frame, a metallic cover mounted on said refractory body having a groove in its upper side, a plurality of roller elements arranged in said groove, a work supporting and enclosing 75 container mounted on the roller elements of said car units, and means for passing a fluid through the body and cover of one of said car units to the interior of said container.

5. A tunnel kiln car having a refractory body, a conduit formed in said body, a metallic cover mounted on said refractory body, a plurality of longitudinal ribs on said cover having a groove in their upper sides, a plurality of supporting elements arranged in 80 said grooves, one of said supporting elements being immovable in said groove, a goods carrying tray mounted on said supporting elements, a box supported on said tray and enclosing the goods carried thereby, a conduit connecting the interior of said box to said body conduit and a gas supply pipe arranged in said body conduit. 85

6. A tunnel kiln car having a refractory body, a vertical conduit in said body, a metallic cover mounted on said refractory body, a plurality of longitudinal ribs on said cover having a groove in their upper sides, a plurality of roller elements arranged in said 90 grooves, one of said roller elements being fixed in said groove, a goods carrying metallic tray mounted on said roller elements, a box supported on said tray and enclosing the goods carried thereby, a conduit in said fixed 95 supporting element connecting the interior of said box to said body conduit, and sealing means for said element conduit. 100

7. A tunnel kiln car having a refractory body, a vertical conduit in said body, a metallic cover mounted on said refractory body, a plurality of longitudinal ribs on said cover having a groove in their upper sides, a plurality of supporting elements in said grooves, one of said elements being fixed in its groove, 115 a goods carrying metallic tray mounted on and having grooved ribs receiving said supporting elements, a box supported on said tray and enclosing the goods carried thereby, conduits formed in one of said tray ribs and in said fixed supporting element and connecting the interior of said box to said refractory body conduit, and grooves extending transversely and longitudinally in said tray goods supporting surface. 120
